UNITED STATES PATENT OFFICE.

GILBERT A. HOGGATT, OF KENMORE, NEW YORK, ASSIGNOR TO CERTAIN-TEED PRODUCTS CORPORATION, OF NEW YORK, N. Y., A CORPORATION OF MARYLAND.

WALL BOARD.

Application filed November 9, 1928. Serial No. 318,132.

This invention relates to the elimination of the wavy and irregular edges often present in the paper going into the manufacture of plaster wallboard. The object of this invention is to eliminate these wavy edges and to secure a feeding of flat wallboard paper into the wallboard machine.

Wallboard paper is dried to about 4% moisture content at the paper mill and it is wound into rolls 40" to 60" in diameter and shipped to the wallboard plants. When exposed to the air this paper will gradually take up moisture along the edges or butts of the rolls in varying amounts depending upon the temperature and relative humidity of the air. Normally it will contain from about 5 to 8% moisture after exposure for any appreciable time. The moisture from the air gradually penetrates the exposed edges or butts of the roll for a distance of 2" to 6" in from the edge of the sheet. The edges of this paper having absorbed moisture, expand, and in running rolls of paper which have been exposed to atmospheric conditions into the wallboard machine it is found that the edges so saturated and expanded, curl up, with the result that the edges are wavy. If these waves are not eliminated before the paper passes through the forming rolls they will quite often remain in the sheet until the gypsum core has set or hardened and the finished board will then have a wavy or irregular edge which is very undesirable.

To eliminate these wavy edges I have found it practical to install heating apparatus directly beneath the edges of the sheets as they go into the plasterboard machine. The heating apparatus may be of any convenient or practicable kind and I do not wish to be limited to the specific form of heater which is herein described as illustrative of my improved method and apparatus.

In the accompanying drawings Figure 1 represents a side elevation of a part of the ordinary plasterboard machine.

Figure 2 is a perspective view of an illustrative example of a heating unit.

Figure 3 is a bottom view of a plasterboard sheet passing over a pair of heaters constructed in accordance with my invention.

Figure 4 is an end view of the plasterboard sheet shown in Figure 3.

In Figure 1, 1 and 2 designate rolls of wallboard paper as they are set up in the plaster-

board machine. 3 represents a guiding roll. 55 4 and 5 are the ordinary forming rolls used in plasterboard manufacture. 10 indicates plaster composition which is fed in between the two sheets. 6 represents the plasterboard sheet as it is fed into the machine. 8 represents a plate of metal, preferably brass, to which a metal angle bar, 9, is attached. The bar 9, may be attached to a convenient support in order to fix the plate, 8, into proper position beneath the edge of the plasterboard sheet. I employ two bar and plate constructions for each sheet, one under each edge. 7 represents the ordinary type of electric space heater which has been found satisfactory in the practice of this invention. A suitable 70 number of these heaters are attached to each plate.

As the plasterboard sheets are fed toward the forming rolls the edges thereof are dried by virtue of the heat supplied directly beneath them through plates 8. It has been found convenient to heat these plates by the common electric space heater, although I do not wish to limit myself to the use of this particular heater as a means of practicing my invention. The electric heaters are convenient because the heat may be controlled by means of switches which allow one, two or three heaters to be energized. The electric heaters occupy a very small space and have 85 been found quite satisfactory in the practice of this invention.

It can be seen that as the wallboard paper passes over these heaters the moisture content along the edges is decreased by virtue of the fact that the moisture present in the edges is vaporized and driven off. Proper regulation of the heat applied in the plates will dry the edges to the same degree of dryness present in the sheet as it comes from the paper mill. Thus the sheet is fed into the plasterboard machine with a uniform moisture content so that the entire sheet is in one plane and there are no expanded or over-saturated portions resulting in wavy or irregular edges. 100

I claim:

1. The method of eliminating wavy edges of wallboard comprising heating the edges of the sheets as they are fed into the wallboard machine to insure a uniform moisture content in said sheet.

2. The method of eliminating the wavy edge of wallboard comprising drying the

edges of the paper sheets as they are fed into the wallboard machine until the moisture content of the sheets is uniform.

3. The method of reducing the moisture content in the edges of a wallboard sheet comprising heating said edges as the sheet is fed into the machine until the moisture content of the sheets is uniform.

4. In combination with a wallboard machine, heating units positioned under the edges of the wallboard sheet as it is fed into the machine.

5. In combination with a wallboard machine, heaters applied directly underneath the edges of the wallboard sheet as it is fed into the machine.

6. In combination with a wallboard machine heaters applied directly beneath the edges of the wallboard sheet as it is fed toward the forming rolls, whereby the wavy edges due to excessive moisture in said sheet are eliminated.

7. In combination with wallboard apparatus, heaters positioned beneath the edges of the wallboard sheet as it is fed from the feed rolls to the forming rolls whereby the moisture content in the wallboard sheet is made uniform to eliminate wavy edges in the finished product.

8. In a wallboard machine, in combination, feed rolls for feeding the cover sheets into the machine, forming rolls for forming the wallboard elements into a sheet of wallboard, and heaters positioned between said feed and forming rolls whereby the moisture content in the cover sheets is made uniform.

9. In a wallboard machine, in combination, feed rolls for feeding the cover sheets into the

machine, forming rolls for forming the wallboard elements into a sheet of wallboard, and heaters positioned between said feed and forming rolls whereby the wavy edges in the finished product are eliminated.

10. In a wallboard machine, in combination, feed rolls for feeding the cover sheets into the machine, forming rolls for forming the wallboard elements into a sheet of wallboard, and heaters positioned between said feed and forming rolls whereby wavy edges in the cover sheets, due to an uneven moisture content thereof, are eliminated.

11. In a wallboard machine, in combination, feed rolls for feeding the cover sheets into the machine, forming rolls for forming the wallboard elements into a sheet of wallboard, and heaters positioned between said feed and forming rolls whereby excess moisture content in the edges of the cover sheets is eliminated and they are straightened before running through the forming rolls.

12. In a wallboard machine, in combination, feed rolls, forming rolls and heaters positioned between the two to dry the cover sheets uniformly.

13. In a wallboard machine, in combination, feed rolls, forming rolls and heaters positioned between said feed and forming rolls to remove, by drying, the waves in the edges of the wallboard sheets.

14. In a wallboard machine, in combination, feed rolls, forming rolls and heaters positioned between said feed and forming rolls whereby all portions of the wallboard sheet are reduced to a uniform moisture content.

In testimony whereof I affix my signature.
GILBERT A. HOGGATT
